UNITED STATES PATENT OFFICE.

WILLIAM COPLAN, OF BALTIMORE, MARYLAND.

NECKTIE.

Application filed October 17, 1925. Serial No. 63,927.

To all whom it may concern:

Be it known that I, WILLIAM COPLAN, a citizen of the United States, and a resident of Baltimore, in the State of Maryland, have ⁵ invented certain new and useful Improvements in Neckties, of which the following is a full, clear, and exact description.

In the manufacture of neckties the larger or tying end of the ties is cut on a bias for ¹⁰ the purpose of giving sufficient elasticity to the material to permit the proper tying of the knot. Of course, the inner lining of the larger end of the tie is also cut on the bias. While it is essential that the larger end of ¹⁵ the tie and the lining be cut on the bias, yet the life of the tie is greatly reduced thereby. For it is apparent that in the tying process the pull that is given to the bias cut material gradually distorts the material, and ²⁰ when thus pulled out of shape the tie is no longer fit for wear. And it is common knowledge that this distortion of the material occurs long before the material has shown signs of wear. Accordingly, the material object of the present invention is to ²⁵ provide means by which the material of the larger end of the tie and its lining may retain their elasticity due to the bias cut, but whereby the tie or its lining will not be ³⁰ come distorted from the tying operation.

Other objects and advantages of the invention will be apparent to those skilled in the art, from the following detailed description, when taken in connection with the accompanying drawings, in which:

Figure 1 is a rear elevational view of a necktie constructed in accordance with my invention; part of the tie being cut away to more clearly show the construction.

Figure 2 is an elevational view of the tie turned inside out.

Figure 3 is a horizontal sectional view taken on line 3—3 of Figure 1; the figure being exaggerated to show the structure.

Figure 4 is a vertical longitudinal sectional view through the lower or tying end of the tie; this figure also being exaggerated to more clearly show the construction; and

Figure 5 is a detail view of the lower end ⁵⁰ of the tie, similar to Figure 1, except that the flaps have been turned back.

Referring to the drawings more in detail, numeral 1 indicates a conventional four-in-hand tie, having the usual larger or tying end 2, and the smaller end 3.

The usual lining is indicated by the numeral 4, and as stated hereinbefore, the lining at the larger end is bias cut. In accordance with the usual practice, however, the lining at the smaller end is straight cut. ⁶⁰

The improved means which I have devised consists of a tape or strip of material ⁵, of any desired width, which is attached to the tie in a manner now to be described.

There is substantially no stretch or elasticity in the smaller end of the tie, for the reason that the lining at that end is cut on the straight, accordingly at that end of the tie my tape or other strip of straight cut material ⁶⁵ 5 is sewed directly to the tie, as clearly shown in the upper part of the cut away section of Figure 1, and in Figures 2 and 3. This strip 5 obviously takes up a very considerable part of the pull on the smaller end of the tie ⁷⁰ during the tying operation and by exerting this pull directly on the tape or strip it is apparent that there will be no tendency for the material of the smaller end of the tie to be stretched out of its proper shape. ⁷⁵ It is thus seen that one of the features of the invention resides in securing the tape directly to the material of the smaller end of the tie. ⁸⁰

Referring now to the larger end of the tie, both the material of the tie and the lining are necessarily cut on the bias; accordingly it is apparent that if the straight cut tape ⁸⁵ 5 be attached directly to the tie or to the lining the result would be that the tie and lining would bulge and wrinkle. It is therefore clear that a bias cut tie and lining cannot be reinforced by attaching directly thereto a strip of straight cut material. ⁹⁰

This difficulty has been overcome by attaching the straight cut tape to the smaller portion of the tie and having it extend through the larger part thereof, but being entirely free of any direct connection with the larger end of the tie or lining. In other words the straight cut tape or strip is simply suspended freely in the larger end of the tie. ⁹⁵

By reference to the drawings it will be noted that the stitching securing the tape to the smaller portion of the tie extends to the point 6, and from that point on to the larger end of the tie the tape merely hangs freely. In order to retain the tape loosely in position, a loop 7 is provided.

In tying the knot of the usual four-in-hand tie, a pull must be exerted on the ¹¹⁰ 110

larger end in order to shape the knot, and it is this strain which distorts the larger end of the tie and renders it useless. In the present construction, however, when the 5 larger end is grasped to shape the knot, the fingers will necessarily grip the tape between the folds of the material, and consequently the pull will be exerted directly on the straight cut tape, thus relieving the tie 10 material and lining of any distorting strain, yet at the same time permitting the same freedom of movement and elasticity to the tie and lining, which is necessary to the proper shaping of the knot.

15 The tape or strip 5 may be of any desired material, and its width will vary with different ties; it being necessary only that it be of such width that it will lie between the fingers when the larger end of the tie is 20 grasped to shape the knot. Further, the point 6, at which the stitching terminates, may vary in different ties.

While I have particularly described my invention as applicable to bias cut ties it 25 will be understood that the invention is by no means of such narrow scope, but is adaptable to ties formed of any elastic material, the broad idea involved in the invention residing in combining a non-elastic 30 strip with an elastic tie, in such manner that the movements of the elastic tie are not affected.

In accordance with the patent statutes I have described what I now believe to be the 35 best embodiment of the invention, but I do not wish to be understood thereby as limiting myself or the scope of the invention, as many changes and modifications may be made without departing from the spirit of 40 the invention; all such I aim to include in the scope of the appended claims.

Having fully described the invention, what I claim as new and desire to secure by Letters Patent is:

45 1. A necktie formed of bias cut material, a lining therefor also cut on the bias, and a reinforcing tape, one portion of said tape being sewed to the tie, and the remaining portion of the tape extending through the 50 remaining portion of the tie but freely movable with respect to the latter portion.

2. A necktie formed of bias cut material, a lining therefor also cut on the bias, and a reinforcing tape, said tape being attached 55 to the smaller end of said tie, and extend-

ing through but freely movable with respect to the larger end.

3. A necktie formed of bias cut material, a lining therefor also cut on the bias, and a reinforcing tape of straight cut material, 60 said tape being attached to the smaller end of said tie, and extending through but freely movable with respect to the larger end of the tie, and means for loosely retaining the free end of the tape in position. 65

4. A necktie formed of bias cut material, a lining therefor also cut on the bias, and a reinforcing tape of straight cut material, said tape being attached to the smaller end of said tie, and extending through but 70 freely movable with respect to the larger portion of the tie, and a loop for loosely retaining the free end of the tape in position.

5. A necktie formed of elastic material, 75 a portion of said tie being necessarily elastic, and another portion not necessarily elastic, and a strip of non-elastic material attached to that portion of the tie which is not necessarily elastic, and extending 80 through the necessarily elastic portion of the tie but freely movable with respect thereto.

6. A necktie formed of elastic material and having a larger and smaller end, and 85 a reinforcing tape, said tape being sewed to the smaller end, and extending through but freely movable with respect to the larger end.

7. A necktie formed of elastic material 90 and having a larger and smaller end, and a reinforcing tape, said tape being sewed to the smaller end, and extending through but freely movable with respect to the larger end, and a loop for loosely retaining the 95 tape in position.

8. A conventional four-in-hand tie formed 100 of bias cut material, a strip of straight cut material extending through but freely movable with respect to the larger or tying end of the tie, said strip being attached to the tie beyond the tying portion thereof.

9. A four-in-hand tie formed of elastic material, a strip of non-elastic material extending through but freely movable with 105 respect to the larger or tying end of the tie, said strip being attached to the tie beyond the tying portion thereof.

WILLIAM COPLAN.
